UNITED STATES PATENT OFFICE.

ANDREW FREDERICK JOHNSON, OF STILLWATER, AND JOHN P. TURNER,
OF ST. PETER, MINNESOTA.

COMBINED BAG-FILLING AND WEIGHING MACHINE.

SPECIFICATION forming part of Letters Patent No. 290,240, dated December 18, 1883.

Application filed April 14, 1883. (No model.)

To all whom it may concern:

Be it known that we, ANDREW FREDERICK JOHNSON, a subject of the King of Sweden and Norway, who has declared his intention of 5 becoming a citizen of the United States, and is a resident of Stillwater, in the county of Washington and State of Minnesota, and JOHN P. TURNER, a citizen of the United States, and residing at St. Peter, Nicollet 10 county, Minnesota, have invented certain new and useful Improvements in Combined Bag-Filling and Weighing Machines, of which the following specification is a full, clear, and exact description, reference being also had to 15 the accompanying drawings.

This invention relates to an apparatus for weighing grain, seeds, meal, &c., but more especially designed to be used in connection with "thrashing-machines," for the purpose 20 of weighing off in sacks the grain thrashed; and it consists in the construction and the arrangement of parts hereinafter shown and described, and then sought to be specifically defined by the claims.

25 In the drawings, Figure 1 represents a front elevation, partly in section. Fig. 2 represents a side elevation; and Fig. 3 represents a plan view with top and platforms and the central hollow post in cross-section, to show 30 the arrangement of scale-balances.

F designates the foot or base on which a hollow post, P', is erected. To the top of this post is fixed a two-spouted top or cap, T' T', provided with a rocking valve, V, upon a 35 rock-shaft, X, and adapted to fit beneath a spout, S, and be connected thereto by hooks e' e', so that the grain falling from the spout will run into which of the spouts T' T' the valve V is set to guide it.

40 L' L² are two horizontal platforms a short distance above the base-frame F, and having upright backs N' N² parallel with and in close proximity to opposite sides of the central post, P'. Upon these platforms bags D D' are placed; 45 the mouths of the bags being held by hooks H around the outsides of the lower ends of the spouts T' T', as shown.

B² B³ are two right-angled metal bars run-

ning across beneath the platforms L' L², upward between the backs N' N² and central 50 hollow post, P', and pivoted by their upper ends at b' b² to the elbows of two bell-crank arms, B B'. These bars B² B³ are securely fastened to the platforms L' L² and backs N' N², and are provided with downwardly-projecting arms a' a², which are adapted to rest 55 against grooved anti-friction pulleys R' R², mounted in the base F, as shown, while the upright parts of the bars rest against similar grooved anti-friction pulleys, R³ R⁴, mounted 60 upon the opposite-sides of the post P'. By this means the platforms L' L², backs N' N², and bars B² B³ may be raised and lowered to a limited extent between the anti-friction rollers with the expenditure of very little power. 65 The two bell-crank arms B B' are pivoted at E E' in slots in the upper part of the post P', with their inner ends overlapping each other inside the hollow post, and connected together by a chain, C², passing downward around a 70 chain-pulley, P. The outer ends of the bell-crank project in an upward and outward direction through slots in the spouts T' T', and are connected to opposite sides of the valve V by chains C and C', and the upper ends of 75 the bars B² B³, as before stated, are pivoted to the bell-crank arms at their "elbows."

Suspended from the pulley P are weights W W' W² W³, corresponding to the amount 80 of grain to be run into either of the bags D or D', as hereinafter shown.

The operation of this device is very simple, and will be readily understood from the drawings.

The weights W W' W² W³ correspond with 85 the kind of grain to be weighed, and the amount each sack D or D' is to hold being varied according to circumstances, wheat requiring one set of weights, oats another set, barley another set, and so on. The apparatus 90 having been set beneath the spout S, and the proper set of weights having been determined upon, they are placed in position, as shown in Fig. 1.

The front of the hollow post P' is provided 95 with a door, M, adapted to be locked at M', to

prevent the weights being tampered with, and after the proper weights are arranged in position this door is closed and locked. The sacks D D' are then suspended from the spouts 5 T' T².

The spout S in the drawings represents the discharge - spout of a thrashing - machine to which the device is especially applicable; but it may be used for sacking and weighing grain 10 in connection with elevators, mills, warehouses, or in any other place where grain is to be handled.

In the drawings the sack D' has just been filled and has overbalanced the adjusted 15 weights W W' W² W³ and caused the bar B³ to pull down the short arm of the bell-crank B', and, through the chain C', thrown the valve V over, so as to turn the grain into the other spout, T², and sack D. Then the sack D' is removed and tied up and an empty one hung in 20 its place upon the spout T' before the sack D is filled. Then when a sufficient quantity of grain has run into the sack D to overbalance the weights the falling of the platform L' and 25 bar B² will throw the valve V over and shoot the grain into the empty sack on the platform L', and so on, filling the sacks alternately and weighing them automatically.

The friction-pulleys R' R² R³ R⁴ permit the 30 platforms to be run up and down with the expenditure of very little force. These anti-friction pulleys, as shown, will be grooved, so that they will act as guides to the bars B² B³ at the same time that they act as anti-friction 35 rollers, and thus cause the platforms to move up and down perpendicularly.

Small plates d' d² will be arranged upon the short arms of the bell-crank levers B B' where 40 they pass through the slots in the spouts to slide up and down the spouts with the movement of the cranks, to cover the slots and prevent the grain leaking through the spouts.

Rods, ropes, or any other suitable means 45 may be used in place of the chains C C' C², if preferred.

A represents a register connected to and adapted to be actuated by the shaft X of the valve V, to record the number of sacks of grain filled and weighed.

We claim—

1. The combination of two alternately rising and falling receptacle-holding platforms, levers from which the said platforms are suspended, a chain or cord connecting the opposite arms of the said levers, and a weight or 55 weights suspended from the said chain or cord, substantially as and for the purpose herein specified.

2. The combination of the platforms L' L², having the right-angled bars B² B³, base F, 60 having central support, P', mounted thereon, bell-crank levers B B', oppositely-branching spouts T' T, having valve V, chains C C', connecting said valve with said crank-arms, chain C², pulley P, and weights W W' W² W³, sub- 65 substantially as and for the purpose specified.

3. The combination of the platforms L' L², backs N' N², bars B² B³, base F, central support, P', anti-friction pulleys R' R² R³ R⁴, crank-arms B B', chain C², pulley P, and weights 70 suspended from said pulley, substantially as specified.

4. The combination of two alternately rising and falling platforms holding the grain-receptacles, levers from which the said platforms are suspended, a chain or cord connecting the opposite ends of the said levers, a weight or weights suspended from the said chain or cord, branching spouts leading to the respective grain - receptacles, a valve alternately closing the said spouts, chains or their equivalent connecting the said levers and valve, and a registering device actuated by the said valve, all substantially as herein specified. 75

In testimony whereof we have hereunto set 80 our hands in presence of two subscribing witnesses.
